TOILET COMB

Filed Nov. 5, 1927

By *John P. Morris*
Attorney

UNITED STATES PATENT OFFICE.

ERIC L. H. COSBY, OF TEDDINGTON, ENGLAND.

TOILET COMB.

Application filed November 5, 1927, Serial No. 231,325, and in Great Britain November 10, 1926.

This invention relates to that class of toilet combs in which the separate teeth, or a number of teeth, are individually or in series or sectionally retained in a removable manner within a backing or holder, so that when it is required to clean the teeth of the comb, the teeth in either form, can be removed for cleaning purposes and be replaced within the holder in a cleanly condition.

10 The object of the present invention is to provide a cushion or resilient means within the holder whereby the teeth or sections of teeth, when the comb is in use will be in engagement with the cushion and the points of 15 the teeth will be caused to follow approximately the different portions of the shape of the head, and thereby obtain a more effective 20 combing of the hair, the cushion or resilient means returning the teeth to their normal 25 position when relieved of pressure. The cushion or resilient means may be of any preferred construction or suitable material and may be in the form of india rubber co- 30 operatively associated with the butt end of each tooth or with the inner edges of the tooth sections and the back of the comb, and such cushion of india rubber may be stretched or relaxed and may be modified in accordance 35 with equivalent structures, or instead of rubber, a resilient metallic strip may be mounted in cooperative relation with the butt ends of the teeth and back of the comb or sections forming the comb, said metal resilient means preferably consisting of curved metal pieces 40 or springs as an auxiliary resilient means with the same advantages in holding the teeth in such manner that they may be caused to conform to the shape of the head or return 45 to normal position.

40 Furthermore, the comb teeth have their butt ends or the sections so constructed that they are adapted to be positively retained within the back or holder, and may be of any desired shape and also so held that the teeth 45 or sections of teeth may be removed and replaced when necessary.

The invention further consists in the details of construction and arrangement of the several parts which will be more fully hereinafter described and claimed.

In the drawing:—

Fig. 1 is a longitudinal vertical section of a comb embodying the features of the invention and particularly showing individually 55 retained and removable teeth.

Fig. 2 is a transverse vertical section on the line *a. a.* Fig. 1.

Fig. 3 is an end elevation of the comb.

Fig. 4 is a bottom plan view of a portion of the comb backing or holder to illustrate 60 the structure shown by Fig. 1, in which individual teeth are separably embodied.

Fig. 5 is a view similar to Fig. 1, showing a modification in construction.

Fig. 6 is a bottom plan view of a portion 65 of the backing or holder of the comb shown by Fig. 5, which is adapted to receive teeth carried in series or sections.

Fig. 7 is a view similar to Figs. 1 and 5 showing a further modification.

Fig. 8 is a transverse vertical section on the line *b. b.* of Fig. 7.

Fig. 9 is a still further side elevation of the comb shown by Fig. 7.

Fig. 10 is a transverse section through the 75 comb shown by Figs. 7 and 9, with interior parts removed.

As shown by Figs. 1, 2 and 3, the backing or holder of the comb comprises a trough-shaped piece of metal A having holes B along 80 its bottom; and a longitudinal rib C projecting from each side, the ends being closed. The teeth D are shaped to fit the holes B and have enlarged or butt ends D' which have a contour adapting them to closely fit the trough 85 A and forming shoulders to bear against the bottom of the trough, around said holes. When all the teeth are positioned in the holes B a strip of soft india rubber E, preferably hollowed out at its top edge as at E', is placed 90 against the enlarged or butt ends D' of the teeth D with a portion of said rubber strip projecting above the trough A. Another trough F having closed ends and formed with internal longitudinal grooves G along its sides 95 closely fits over the trough A. After these troughs have been assembled, they become temporarily locked together by reason of the engagement of the ribs C with the grooves G and slightly compress the rubber E inside of 100 the same, the rubber serving to maintain the engagement of the trough A with the sides of the trough F, the trough A being adapted to yield slightly to insure a temporary locking association of the two troughs. The rubber 105 strip or cushion means E will exert pressure upon the enlarged upper ends or butts D' of the teeth D, so that any pressure on one or more of these teeth during the use of the comb will be transmitted to the cushion E which 110

will yield to and allow the tooth or teeth to recede and thus permit the points of the teeth to adjust themselves to the contour of the head. At any time desired and found necessary, the two troughs A and F may be separated, the rubber cushion E may be removed and the teeth D may be withdrawn from the trough A and afterwards reset and the parts then reassembled as just explained. The teeth 10 D project through the openings B in the bottom of the trough A, as shown by Fig. 4, so that said teeth are thus retained in positively applied position.

Figs. 5 and 6 show a modification of the 15 structure wherein the bottom of the trough A is formed with slots J instead of with a plurality of openings B as heretofore described, and the teeth H are formed in sections of a predetermined number and project from a 20 flexible back I, the said back being larger in dimensions than the upper portions of the teeth which extend therefrom so that a reliable support will be formed for the said sections of the flexible back. The sectional backs 25 I are provided with extensions H' at their ends to properly space and assist in the retention of these sections in the trough A in the same manner as in the case of the single teeth. To remove the teeth or sections of 30 teeth in this modified form, the two troughs are pulled apart, when the teeth sections forming the comb may be withdrawn. Otherwise the structure shown by Figs. 5 and 6 is similar to that illustrated by Figs. 1 to 3, inclusive.

In the further modification shown by Figs. 7 to 10, inclusive, the comb section K is continuous and has back K' of flexible or yielding character. The holder or backing in this instance is composed of two pieces L and M of metal or analogous material having their upper edges bent at right angles toward one another, as at L' and M', the piece or member L' fitting inside the piece or member M, the lower 45 ends of the end portions of these pieces or members being slightly lengthened or formed with extensions which are connected by pivots N to form hinges N' for retaining the comb K within the holder. In this construction the 50 comb is provided with end extensions K² to which are pivoted the outer ends of curved leaf springs P which have their free ends reversely projecting towards the center of the comb back K' and against which they bear. 55 In assembling the parts L and M of the holder are opened on the hinge connections, and a strip Q of india rubber is inserted in the portion L and positioned next to the angular bent upper edge or flange L' of the member L. 60 The leaf springs P are then slightly compressed or flattened, and the comb K with the springs is then inserted between the open pieces or members L and M with the springs P bearing against the rubber cushion Q and 65 with the ends K² of the comb resting against

the hinges N', as shown by Fig. 7. When the two pieces or members L and M are closed the comb springs and india rubber will be properly associated, and the two pieces or members L and M will be held closed by engagement of a projection R at or about the center of the angular bent upper edge or flange L' with a hole or opening S in the wall of the angular or bent upper edge or flange M' of the piece or member M. The back K' 70 of the comb K being flexible, will permit the teeth to yield and conform to the contour of the head, as in the forms of the device heretofore described. When the two pieces or members L and M are closed and secured, 80 the rubber Q and springs P will be enclosed, as shown by Fig. 9, but at any time desired the members L and M may be opened to permit the removal of the comb and its springs for cleaning or other purposes. 85

In all of the forms of the device shown, the essential features will be present, whether the teeth of the comb be constructed as single units, in sections, or as a single part; that is to say, the teeth may yield so that the points of the teeth will conform to the contour of the head. In those instances where it is preferred to use rubber any construction of rubber cushion adapted for the purpose may be used, and the yielding action thereof will extend 90 throughout the length of the comb. By interposing the rubber cushion Q between the springs P and the back of the comb, as shown in Figs. 7 to 10, an auxiliary cushion effect is provided which, combined with the resilient 95 back K', will result in a closer conformation of the points of the comb with the contour of the head, and moreover in this instance it is not necessary that the rubber cushion Q be hollowed out or reduced along its upper edge 100 as in the forms shown by Figs. 1 and 5.

In all the forms of the improved comb it will be observed that sufficient play or space is provided in the holder backing for the yielding action of the teeth of the comb and that either the hollowed out or channel portion E' of the rubber cushion E, as shown by Figs. 1 and 5, and the space between the back K' of the comb K or the rubber cushion Q, as shown by Figs. 7 and 8, will give freedom to 105 the alternate depression and normal extension of the comb teeth during the use of the comb to conform to the irregularities of the contour of the head. In some instances, the rubber cushion Q, shown by Figs. 7 and 8, may 110 be omitted, and the springs P may act alone as the main cushion means between the comb back and the holder or backing of the entire comb.

It will be understood that such changes as 115 fairly fall within the scope of the appended claims in the details of construction and arrangement of the several parts may be adopted without departing from the nature or spirit of the invention. 120

What is claimed as new is:—

1. A toilet comb, comprising a hollow backing, comb teeth removably mounted in said backing, and yielding cushion means between the teeth and backing against which the teeth are depressible to automatically conform to the contour of the head.
2. A toilet comb comprising a hollow backing, comb teeth movably mounted in said backing, and cushion means between the comb teeth and backing against which the teeth are depressible to conform to the contour of the head.
3. A toilet comb comprising a backing and teeth removably mounted in said backing, the teeth being longitudinally depressible from and automatically extended to normal position relatively to said backing to conform to the contour of the head.
4. A toilet comb comprising a holder, a plurality of comb teeth sections having their backs mounted in said holder, and cushion means within the holder and operating on backs of said sections to normally maintain the teeth of said sections projected from the holder and to permit said teeth to conform to the contour of the head.
5. In a toilet comb, the combination of a hollow backing, a comb organization mounted in said backing, and resilient means interposed between the comb organization and the backing and tending to hold the teeth of said organization projected from said backing, space being provided in said backing to permit the comb organization to recede within the backing to conform to the contour of the head.
6. A toilet comb comprising a comb-tooth organization, a holder formed of a plurality of separable parts and in which said comb

organization is removably held, one of said holder parts having an opening through which the teeth of said comb-tooth organization project.

7. A toilet comb according to claim 6 where- 45
in the comb-tooth section is depressible in the holder in the direction of the length of the teeth of said section.

8. A toilet comb according to claim 6 where- 50
in yieldable means is contained in said holder behind the comb-tooth section and against which the comb-tooth section is depressible.

9. A toilet comb comprising a comb-tooth section, and a holder in which said comb-tooth section is mounted for movement in the 55
direction of the length of the teeth of the latter, said holder being formed of a pair of separable parts to permit the insertion of said comb-tooth section therein and its removal therefrom, said holder and comb-tooth sec- 60
tion having interengaging means to prevent the removal of said comb-tooth section from said holder when said section and holder are assembled.

10. A toilet comb comprising a comb-tooth 65
section having shoulders projecting from its back, and a holder in which said comb-tooth section is removably mounted, said holder being formed of a pair of separable parts to permit the insertion of said comb section 70
therein and its removal therefrom, said holder having means to engage with the shoulders of said comb section to secure said comb-tooth section against removal from said holder when said section and holder are 75
assembled.

In testimony whereof I have hereunto set
my hand.

ERIC L. H. COSBY.
